GAS HEATER

Eric G. Peterson, New York, and David P. Graham, Westbury, N. Y., assignors to Peabody Engineering Corporation, New York, N. Y., a corporation of New York

Application October 5, 1944, Serial No. 557,268

11 Claims. (Cl. 263—19)

1

This invention relates to heat exchangers and more particularly to heaters for heating fluids under pressures up to several atmospheres, and has for an object to provide a fluid heater of the above type having novel and improved details of construction and features of operation.

In accordance with the present invention we provide an all metal fluid heater having novel and improved means for protecting both the outer and inner shells against the high temperatures. In one embodiment the heater is provided with one or more concentric passages within the outer shell through which the gases to be heated pass. A corrugated spacing member is disposed in each passage to form a plurality of separated axial channels for the gases. The spacing member strengthens the assembly and also provides an internal shield to prevent direct radiation of heat from the inner wall to the outer wall of each concentric passage. It also greatly increases the surface area for heat transfer from the metal to the gases. These combined effects prevent either the exterior shell or interior shell from reaching too high a temperature, and eliminate the need for a refractory liner.

The invention is particularly applicable to gas heaters of the type used for heating air or other combustion supporting gases for catalytic cracking processes or for the operation of gas turbines. Such heaters include a burner firing into a combustion chamber and passages to supply gases to be heated in heat exchange relation thereto for preheating and to discharge the gases into the combustion chamber to be mixed with products of combustion for final heating. If the heater is to be used for heating air or other combustion supporting gases a portion thereof may be supplied to the burner to support combustion. An adjustable member, such as a baffle, may be provided to control the amount of gas which passes directly into the burner to support combustion and the amount which passes through the pre-heating passages for subsequent mixture with the products of combustion.

The invention also provides for maintaining uniform combustion across the combustion chamber area and for regulating the temperature distribution thereacross. In one embodiment the burner includes an air register having peripheral air doors provided with individual adjusting means for controlling the air distribution.

Although the novel features which are believed to be characteristic of this invention are pointed out more particularly in the claims appended hereto, the invention will be better understood by

2

referring to the following description, taken in connection with the accompanying drawings in which specific embodiments thereof have been set forth for purposes of illustration.

5 In the drawings:

Fig. 1 is a longitudinal section taken on the line 1—1 of Fig. 2 showing a gas heater embodying the present invention;

10 Fig. 2 is a transverse section taken on the line 2—2 of Fig. 1;

Fig. 3 is a broken longitudinal section through a gas heater illustrating a further embodiment of the invention; and

15 Fig. 4 is a partial transverse section taken on the line 4—4 of Fig. 3.

20 Referring to the drawings more in detail, the heater is shown in Fig. 1 as comprising an outer cylindrical pressure resisting shell 10 secured to a head ring 11 which is attached by means of bolts 12 to a flange 13 formed on a fuel burner register front plate 14.

25 The front plate 14 carries an air register 15 of standard type having a plurality of peripheral air doors 16 through which air is admitted for combustion to a throat piece 17 which is shown as attached to the register 15 and as flaring outwardly and terminating in a radial flange 18 around which auxiliary air for combustion and cooling flows in a manner to be described. The 30 throat piece 17 is shown as provided with holes 17a through which air is supplied to the interior of the throat piece for cooling purposes and for controlling combustion. The doors 16 are shown as regulated simultaneously by a handle 20 which is attached to one of the doors 16. Suitable links 20a connect the doors for operation in unison.

35 The air register 15 is shown as attached to an inner plate 22 which is provided with a flange 23 by which it is attached to the flange 13 of the 40 front plate 14 and is spaced from the front plate to receive suitable heat insulation 24 therebetween.

An atomizer 30 for atomizing pulverized, liquid or gaseous fuel extends through the front plate 45 14 axially of the furnace and is provided with a tip 31 from which the atomized fuel is ejected for combustion. The atomizer 30 may be of standard construction, for example, that shown in the Fisher Patent 1,326,488, dated December 30, 1919. The atomizer includes a diffuser 32 which is positioned to cooperate with the burner throat 17 for directing the spray of fuel as required to obtain efficient combustion. An igniter 33 may also be provided. The air doors 16 50 admit air for combustion around the entire per-

periphery of the burner throat and cause the same to rotate as it advances between the diffuser 32 and the throat 17 to be mixed with the fuel for combustion.

A metal liner 35 is separated from the shell 10 to provide an annular air passage 36 therebetween and is positioned relative to the shell 10 by a corrugated spacing member 37 which extends around the entire periphery of the shell to separate the passage 36 into a plurality of independent channels as indicated at Fig. 2.

A second concentric passage 40 is formed by a plurality of units 40a consisting of concentric rings 41 and 42 and corrugated spacing members 43 similar to the corrugated spacing member 37 above mentioned which space the rings to provide the air passage 40 therebetween. The units are of a size to be inserted within the liner 35 and to be carried thereby. The rings 41 constitute the side wall of the combustion chamber. In the embodiment shown in Fig. 1 a plurality of such units are disposed along the combustion chamber. The rings 41 of the various units are made progressively of increased diameter so that each ring 41 is offset with respect to the preceding ring 41 to provide an air passage 44 therebetween through which a portion of the air from the passage 40 enters the combustion chamber. The spacing members 37 increase the heat transfer to the gases and with the liner 35 serve to center and support the units 40a. If the units 40a are not required to be self-contained the rings 42 may be omitted and the spacing member attached directly to the liner 35.

Suitable vanes may be provided for directing the air which passes through the annular passages 44. In the embodiment shown an axial vane 45 is attached to the wall 41 of the second unit and extends parallel to the wall 41 of the next succeeding unit to cause the air which enters the combustion chamber through the corresponding passage 44 to flow along the periphery of the chamber.

A conical shaped vane 46 is shown as attached to the wall 41 of the fourth unit in a position to direct the air which passes through the preceding passage 44 radially toward the axis of the chamber.

It is to be understood that similar vanes may be attached to the various units so as to cooperate with each of the passages 44 and may be arranged to direct the air as desired either radially toward the axis of the chamber or axially along the periphery thereof.

The walls 41 of the successive units are offset so that passages 40 are of decreasing area suited to maintain a uniform velocity of air as the quantity of air is reduced due to the introduction of progressive amounts into the combustion chamber through the passages 44.

It is to be understood that the passages 40 may be built up of any desired number of units and that the units may be all of the same size if desired. The units may be made segmental if desired to facilitate assembly and removal. The inner shell 41 may be solid omitting passages 44 if desired.

A ring 50 attached to the ring 41 of the first unit forms a chamber 51 communicating with both the passage 36 and the passage 40 and arranged to cause the air or gases which are passed through the passage 36 in a direction toward the burner end of the heater to reverse and flow through the passages 40 to the opposite ends of the heater. The chamber 51 also is open to an

air chamber 52 surrounding the air register 30 so that a portion of the air (or other combustion supporting gas) which passes through the passage 36 flows through the air register and into the burner throat whereas the remainder of the air passes through the passages 40 to be mixed with the combustion gases.

The amount of combustion air passing to the air register chamber may be regulated by suitable means shown in Fig. 1 as a baffle 53 which is mounted for axial movement within the shell 10 and is adjusted by rods 54 which are shown as attached by universal joints 55 to the baffle 53 and which extend through the head ring 11 and flange 18 and are provided with actuating handles 56. The rods 54 are threaded through bosses 57 attached to the head ring 11 so that they are advanced axially by rotation of the handle 56. When in closed position the baffle 53 engages the ring 50 to close the chamber 51 and prevent passage of air into the air register chamber 52. Air from the air register chamber 52 also passes into the combustion chamber between the ring 50 and the flange 18 of the burner throat. Consequently, controlled quantities of air are admitted at various axially spaced zones along the combustion chamber. A ring 58 is shown as provided at the burner throat for supplying gaseous or pulverized fuel when desired from a supply pipe (not shown).

The exit end of the heater is formed by a conical section 60 of the shell 10 having a flange 61 which is secured by bolts 62 to a flange 63 carried by a duct 64. An air supply duct 65 extends through the conical section 60 into registration with a conical passage 66, formed between the conical section 60 and an inner conical member 68. The passage 66 is closed at one end by a cylindrical liner 69 and is open at the other end to the passage 36. Suitable heat insulation 70 is provided around the conical section 60 of the pressure shell 10. The final passage 40 opens into the combustion chamber near the zone of the conical liner 68. The duct 65 is provided with a flange 71 for attachment to a supply pipe not shown.

Operation

In the operation of this device, air or other gases to be heated are passed through the duct 65 into the chamber 66; thence through the passage 36 to the chamber 51 at the burner end of the heater; thence through the various passages 40 from which successive portions of the air are withdrawn through the annular passages 44 and are supplied to the combustion chamber for mixing with the combustion gases, the remainder issuing from the open end of the final passage 40 at the discharge end of the combustion chamber. A controlled portion of the gases from the passage 36 enters the air register chamber 52 and passes through the air register doors and through the burner throat 17. The hot products of combustion pass through the duct 64 at the exit end of the combustion chamber and may be supplied for utilization to any desired piece of equipment such as a catalyst chamber or a gas turbine.

The gases, in passing through the passage 36, are preheated and in passing through the return passages 40 are further heated before they are supplied to the combustion gases. The portion of the gases which enter the combustion chamber around the burner throat and through the successive passages 44 serve to control the combustion and the temperature of the com-

bustion gases as they pass along the combustion chamber and also absorb heat from the combustion gases and thereby protect the inner walls 41 from the intense heat of combustion.

As above pointed out, the corrugated spacing members 37 and 43 increase the area available for heat transfer by convection to the gases passing through the corresponding passages and also prevent direct passage of heat by radiation from the inner walls 41 to the outer wall 42 of the inner passage and from the inner wall 35 to the shell 10 of the outer passage. In this way it is possible to maintain the shell 10 and walls 41 at a sufficiently low temperature without the use of a refractory lining. At the same time the corrugated members 37 and 43 position the assembly.

The above described furnace has been found to operate efficiently and to be well suited for commercial operation wherein high pressures and high rate of heat transfer to the gases is required. The inner rings 41 may be corrugated if desired instead of smooth as shown so as to increase the area available for heat transfer.

Fig. 3

Referring now to Fig. 3, a modified form of heater is shown which is the same general construction as the heater shown in Figs. 1 and 2 above described. To avoid repeating the description the corresponding parts have been given the same reference characters. In the embodiment of Fig. 3, however, a separate cooling medium is passed through the outer passage 36 and the air to be heated is introduced in the burner end of the shell and makes only a single passage along the combustion chamber. In this embodiment the burner end of the passage 36 is closed by a ring 80 and a duct 81 communicates therewith to receive the fluid which has entered through the duct 65 and is passed along the passage 36 for cooling the outer shell 10.

A duct 85 communicates with both the air register chamber 52 and the passage 40. The air supply to the chamber 52 and the passage 40 is controlled by division plate 86 and an adjustable damper 87 attached thereto the position of which may be varied to control the relative amounts of air supplied to the two sides of the division plate 86.

The outer passage 36 is formed by a liner 10a and liner 35 separated by a corrugated spacing member 37 as above described, and the inner passages 40 are formed by units 40a provided with the corrugated spacing members 43 as above described. The liner 10a, spacing member 37 and liner 35 constitute a unit or cartridge which may be readily inserted within the shell 10 and the units 40a are insertable in the liner 35. Assembly of the heater is thus facilitated. The member 37 terminates at the duct 88 to provide an annular passage 88 around the shell through which fluid passes from the various individual channels produced by the corrugated spacing member to the exhaust duct 89. In Fig. 3 the air doors 16 are provided with individual control handles 20 which permit adjustment of the air distribution around the burners. These doors may be adjusted to obtain uniform temperature across the entire combustion chamber.

In this embodiment liquids or gases other than combustion supporting gases may be passed through the outer passage 36. The construction and operation are otherwise similar to that of the embodiments shown in Figs. 1 and 2 and described above.

It is to be noted that the cartridge construction including the corrugated spacing members is applicable to an unfired heat exchanger omitting the burner and combustion chamber, to promote heat transfer between fluids in the respective adjacent passages.

Although specific embodiments of the invention have been shown for purposes of illustration, it is to be understood that various changes and modifications may be made therein as will be apparent to a person skilled in the art. The invention is only to be restricted in accordance with the scope of the following claims.

What is claimed is:

15. A heat exchanger comprising a closed shell, an inner liner spaced from said shell to form an annular fluid passage, a corrugated spacing member in said passage supporting said inner liner and dividing said annular passage into a plurality of separate axial channels, a second concentric liner disposed within said first inner liner and separated therefrom by a corrugated separator to form a second set of axial channels, and means supplying fluid to one of said passages.
20. A gas heater comprising a closed shell forming a combustion chamber, a burner within said shell, said burner including fuel admission means and an air register to supply air for combustion, an inner liner spaced from said shell to form an annular fluid passage, a corrugated spacing member in said passage supporting said inner liner and dividing said annular passage into a plurality of separate axial channels, a second concentric liner disposed within said first inner liner and separated therefrom by a corrugated separator to form a second set of axial channels, an inlet duct supplying fluid to said first channels, means causing said fluid to flow serially through the two sets of passages and means discharging the fluid from said second passages into the combustion chamber for mixing with the combustion gases.
25. A gas heater comprising a closed shell forming a combustion chamber, a burner within said shell, said burner including fuel admission means and an air register to supply air for combustion, an inner liner spaced from said shell to form an annular fluid passage, a corrugated spacing member in said passage supporting said inner liner and dividing said annular passage into a plurality of separate axial channels, a second concentric liner disposed within said first inner liner and separated therefrom by a corrugated separator to form a second set of axial channels, an inlet duct supplying fluid to said first channels, means causing said fluid to flow serially through the two sets of passages and means discharging the fluid from said second passages into the combustion chamber for mixing with the combustion gases, and means supplying a portion of the fluid from said channels to said air register for combustion.
30. A gas heater comprising a closed shell forming a combustion chamber, a burner within said shell, said burner including fuel admission means and an air register to supply air for combustion, an inner liner spaced from said shell to form an annular fluid passage, a corrugated spacing member in said passage supporting said inner liner and dividing said annular passage into a plurality of separate axial channels, a second concentric liner disposed within said first inner liner and separated therefrom by a corrugated separator to form a second set of axial channels, an inlet duct supplying fluid to said first channels, means causing said fluid to flow serially through the two sets of passages and means discharging the fluid from said second passages into the combustion chamber for mixing with the combustion gases, and means supplying a portion of the fluid from said channels to said air register for combustion.
35. A gas heater comprising a closed shell forming a combustion chamber, a burner within said shell, said burner including fuel admission means and an air register to supply air for combustion, an inner liner spaced from said shell to form an annular fluid passage, a corrugated spacing member in said passage supporting said inner liner and dividing said annular passage into a plurality of separate axial channels, a second concentric liner disposed within said first inner liner and separated therefrom by a corrugated separator to form a second set of axial channels, an inlet duct supplying fluid to said first channels, means causing said fluid to flow serially through the two sets of passages and means discharging the fluid from said second passages into the combustion chamber for mixing with the combustion gases, and means supplying a portion of the fluid from said channels to said air register for combustion.
40. A gas heater comprising a closed shell forming a combustion chamber, a burner within said shell, said burner including fuel admission means and an air register to supply air for combustion, an inner liner spaced from said shell to form an annular fluid passage, a corrugated spacing member in said passage supporting said inner liner and dividing said annular passage into a plurality of separate axial channels, a second concentric liner disposed within said first inner liner and separated therefrom by a corrugated separator to form a second set of axial channels, an inlet duct supplying fluid to said first channels, means causing said fluid to flow serially through the two sets of passages and means discharging the fluid from said second passages into the combustion chamber for mixing with the combustion gases, and means supplying a portion of the fluid from said channels to said air register for combustion.
45. A gas heater comprising a closed shell forming a combustion chamber, a burner within said shell, said burner including fuel admission means and an air register to supply air for combustion, an inner liner spaced from said shell to form an annular fluid passage, a corrugated spacing member in said passage supporting said inner liner and dividing said annular passage into a plurality of separate axial channels, a second concentric liner disposed within said first inner liner and separated therefrom by a corrugated separator to form a second set of axial channels, an inlet duct supplying fluid to said first channels, means causing said fluid to flow serially through the two sets of passages and means discharging the fluid from said second passages into the combustion chamber for mixing with the combustion gases, and means supplying a portion of the fluid from said channels to said air register for combustion.
50. A gas heater comprising a closed shell forming a combustion chamber, a burner within said shell, said burner including fuel admission means and an air register to supply air for combustion, an inner liner spaced from said shell to form an annular fluid passage, a corrugated spacing member in said passage supporting said inner liner and dividing said annular passage into a plurality of separate axial channels, a second concentric liner disposed within said first inner liner and separated therefrom by a corrugated separator to form a second set of axial channels, an inlet duct supplying fluid to said first channels, means causing said fluid to flow serially through the two sets of passages and means discharging the fluid from said second passages into the combustion chamber for mixing with the combustion gases, and means supplying a portion of the fluid from said channels to said air register for combustion.
55. A gas heater comprising a closed shell forming a combustion chamber, a burner within said shell, said burner including fuel admission means and an air register to supply air for combustion, an inner liner spaced from said shell to form an annular fluid passage, a corrugated spacing member in said passage supporting said inner liner and dividing said annular passage into a plurality of separate axial channels, a second concentric liner disposed within said first inner liner and separated therefrom by a corrugated separator to form a second set of axial channels, an inlet duct supplying fluid to said first channels, means causing said fluid to flow serially through the two sets of passages and means discharging the fluid from said second passages into the combustion chamber for mixing with the combustion gases, and means supplying a portion of the fluid from said channels to said air register for combustion.
60. A gas heater comprising a closed shell forming a combustion chamber, a burner within said shell, said burner including fuel admission means and an air register to supply air for combustion, an inner liner spaced from said shell to form an annular fluid passage, a corrugated spacing member in said passage supporting said inner liner and dividing said annular passage into a plurality of separate axial channels, a second concentric liner disposed within said first inner liner and separated therefrom by a corrugated separator to form a second set of axial channels, an inlet duct supplying fluid to said first channels, means causing said fluid to flow serially through the two sets of passages and means discharging the fluid from said second passages into the combustion chamber for mixing with the combustion gases, and means supplying a portion of the fluid from said channels to said air register for combustion.
65. A gas heater comprising a closed shell forming a combustion chamber, a burner within said shell, said burner including fuel admission means and an air register to supply air for combustion, an inner liner spaced from said shell to form an annular fluid passage, a corrugated spacing member in said passage supporting said inner liner and dividing said annular passage into a plurality of separate axial channels, a second concentric liner disposed within said first inner liner and separated therefrom by a corrugated separator to form a second set of axial channels, an inlet duct supplying fluid to said first channels, means causing said fluid to flow serially through the two sets of passages and means discharging the fluid from said second passages into the combustion chamber for mixing with the combustion gases, and means supplying a portion of the fluid from said channels to said air register for combustion.
70. A gas heater comprising a closed shell forming a combustion chamber, a burner within said shell, said burner including fuel admission means and an air register to supply air for combustion, an inner liner spaced from said shell to form an annular fluid passage, a corrugated spacing member in said passage supporting said inner liner and dividing said annular passage into a plurality of separate axial channels, a second concentric liner disposed within said first inner liner and separated therefrom by a corrugated separator to form a second set of axial channels, an inlet duct supplying fluid to said first channels, means causing said fluid to flow serially through the two sets of passages and means discharging the fluid from said second passages into the combustion chamber for mixing with the combustion gases, and means supplying a portion of the fluid from said channels to said air register for combustion.
75. A gas heater comprising a closed shell forming a combustion chamber, a burner within said shell, said burner including fuel admission means and an air register to supply air for combustion, an inner liner spaced from said shell to form an annular fluid passage, a corrugated spacing member in said passage supporting said inner liner and dividing said annular passage into a plurality of separate axial channels, a second concentric liner disposed within said first inner liner and separated therefrom by a corrugated separator to form a second set of axial channels, an inlet duct supplying fluid to said first channels, means causing said fluid to flow serially through the two sets of passages and means discharging the fluid from said second passages into the combustion chamber for mixing with the combustion gases, and means supplying a portion of the fluid from said channels to said air register for combustion.

centric liner disposed within said first inner liner and separated therefrom by a corrugated separator to form a second set of axial channels, an inlet duct supplying fluid to said first channels, means causing said fluid to flow serially through the two sets of passages and means discharging the fluid from said second passage into the combustion chamber for mixing with the combustion gases, means supplying a portion of the fluid from said channels to said air register for combustion, and adjustable means controlling the relative quantity thus supplied to the air register.

5. A gas heater comprising a closed shell forming a combustion chamber, a burner within said shell, an inner liner spaced from said shell to form an annular gas passage, a corrugated spacing member in said passage and dividing said annular passage into a plurality of separate axial channels, a second concentric liner separated by a corrugated separator from said first liner and disposed within said first inner liner to form a second set of axial channels unconnected with the first channels, an inlet duct supplying gas to said first channels, means supplying other gas to said second channels, and means discharging the gas from said second channels into the combustion chamber for mixing with the combustion gases.

6. A fluid heater comprising a closed shell forming a combustion chamber having a discharge opening at one end, a burner within said shell at the other end, said burner including fuel admission means and an air register to supply air for combustion, an inner liner spaced from said shell to form an annular fluid passage extending from the zone of the burner to the zone of said discharge opening, a corrugated spacing member in said passage supporting said inner liner and dividing said annular passage into a plurality of separate axial channels, a second concentric liner separated by a corrugated spacing member from said liner and disposed within said first inner liner to form a second set of axial channels unconnected with the first set, an inlet duct supplying fluid to said first channels, an outlet duct communicating with said first channels, a second inlet duct connected to supply air for heating to said second channels, and means supplying a portion of said air from said last duct to said air register for combustion.

7. A fluid heater comprising a closed shell forming a combustion chamber having a discharge opening at one end, a burner within said shell at the other end, said burner including fuel admission means and an air register to supply air for combustion, an inner liner spaced from said shell to form an annular fluid passage extending from the zone of the burner to the zone of said discharge opening, a corrugated spacing member in said passage supporting said inner liner and dividing said annular passage into a plurality of separate axial channels, a second concentric liner separated by a corrugated spacing member and spaced from said first liner and disposed within said first inner liner to form a second set of axial channels unconnected to the first set of channels, an inlet duct supplying fluid to said first channels, an outlet duct communicating with said first channels, a second inlet duct connected to supply air for heating to said second channels, means supplying a portion of said air from said last duct to said air register for combustion, and adjustable means controlling said portion.

8. A heat exchanger comprising a shell having a combustion chamber with a discharge opening at one end, a burner within said shell at the other end, said burner including fuel admission means and an air register having adjustable peripheral doors to supply air for combustion and to cause same to rotate, an inner liner spaced from said shell to form an annular fluid passage, other concentric liners disposed within said first inner liner to form additional fluid passages, an inlet duct supplying fluid to said first passage, an outlet duct communicating with said first passage, a second inlet duct connected to supply air to said heat exchanger, means supplying a portion of said air from said last duct to said other passages for heating and means supplying another portion of said air from said last duct to said air register for combustion, and adjustable means controlling the relative values of said portions.

10 9. A gas heater comprising a closed shell, a burner within said shell, said burner including fuel admission means and an air register having peripheral air inlet means to supply air for combustion and to cause the air to rotate, an inner metal liner forming a combustion chamber and spaced from said shell to form an annular air passage therebetween, a longitudinally corrugated spacing member in said passage supporting said liner and dividing said annular passage into a plurality of separate axial channels, an air connection supplying air to the air register end of said passage, discharge means to discharge said air from said passage into the combustion chamber to mix with the products of combustion, a duct supplying a portion of said air from said air connection to said air register for combustion, and adjustable means controlling the relative quantity of said air supplied to said air register and said passage.

30 10. A gas heater comprising a closed shell, a burner within said shell, said burner including fuel admission means and an air register having peripheral air inlet means to supply air for combustion and to cause the air to rotate, an inner metal liner forming a combustion chamber and spaced from said shell to form an annular air passage therebetween, a longitudinally corrugated spacing member in said passage supporting said liner and dividing said annular passage into a plurality of separate axial channels, an air connection supplying air to the air register end of said shell, a transverse division plate in said shell in registry with said air connection to form separate air ducts communicating respectively with said air register and with said axial channels, and means to adjust the relative quantities of air supplied to said separate ducts.

60 11. A gas heater comprising a closed shell, a burner within said shell, said burner including fuel admission means and an air register having peripheral air inlet means to supply air for combustion and to cause the air to rotate, an inner metal liner forming a combustion chamber and spaced from said shell to form an annular air passage therebetween, a longitudinally corrugated spacing member in said passage supporting said liner and dividing said annular passage into a plurality of separate axial channels, an air connection supplying air to the air register end of said shell, a transverse division plate in said shell in registry with said air connection to form separate air ducts communicating respectively with said air register and with said axial channels, and an adjustable vane on said division plate to adjust

the relative quantities of air supplied to said separate air ducts.
